(57) **CLAIM**

The ornamental design for a coffee press, as shown and described.

DESCRIPTION

FIG. 1 is a perspective view of a coffee press showing the new design;

FIG. 2 is an elevation view of a first side of the coffee press shown in FIG. 1;

FIG. 3 is an elevation view of a second side of the coffee press shown in FIG. 1;

FIG. 4 is an elevation view of a first end of the coffee press shown in FIG. 1;

FIG. 5 is an elevation view of a second end of the coffee press shown in FIG. 1;

FIG. 6 is a top view of the coffee press shown in FIG. 1; and, FIG. 7 is a bottom view of the coffee press shown in FIG. 1.

The broken lines shown in the drawings illustrate portions of the coffee press and form no part of the claimed design.

1 Claim, 7 Drawing Sheets
